 Newark, N. J., a corporation of Delaware

Application January 30, 1943, Serial No. 474,094

13 Claims. (Cl. 250—9)

1

This application is a continuation in part of my copending application, Serial No. 445,944, filed June 5, 1942.

The present invention relates to systems for combining two or more signals and more particularly to such systems wherein at least one of said signals may be a course determining signal.

It is an object of my invention to provide a system for interconnecting two modulated radio frequency sources to a common line or load without substantial loss of radio frequency power.

It is a further object of my invention to provide an arrangement wherein two separate sources of modulated radio frequency may be interconnected to supply modulated energy to a common load in conjugate relation with a minimum of energy dissipation.

It is a further object of my invention to provide a system for radiating directively signals defining a course line while at the same time radiating upon the same wavelength further signals such as signals representing speech and/or signals representing a further course line. More particularly it is an object to provide such a system wherein both signals shall be radiated from one common antenna element while one of the signals, preferably the course line-defining signal, is additionally radiated from further antenna elements.

It is a further object to provide such a system wherein voice signals may be radiated from an element of a directive array used for beacon purposes while at the same time insuring that the voice signals shall not react upon the output stage delivering the beacon signals or vice versa.

It is a still further object of my invention to provide a system which shall simultaneously radiate directional signals for aiding navigation and other signals such as speech signals without any interaction between the sources of the two signals and without requiring that 50% of the power from each source shall be dissipated in so-called "dumps" or matching resistors.

When combining two signals (e. g., directive beacon signals and speech signals) for application to a single antenna element (or to a group of antenna elements connected together so as to act as a single antenna means) or other load, it is necessary that the connections be made so as to maintain approximate conjugacy between the two sources of signals (i. e., between the source of the beacon signals and the speech signal source). In other words, the connections should be made in such fashion that the varying voltage from the speech signal source shall have

2

no effect at the output of the source of the beacon signals and vice versa. This requires that the two sources while being both coupled to the single antenna means must nevertheless not be coupled to one another. In order to attain such conjugacy various types of so-called conjugate networks may be used, such networks including the well-known "Wheatstone" bridge, the hybrid coil arrangement commonly used in carrier telephony

10 and other types of arrangements specifically designed for coupling two sources to a load without intercoupling the two sources to each other. One of the most practical forms of conjugate network for use at high radio frequencies is the type disclosed in my United States Patent No. 2,147,809 issued February 21, 1939, for "High frequency bridge circuit and high frequency repeaters", wherein there is described a sort of bridge made up of four lengths of 2-wire transmission lines connected together in a square closed loop with a transposition in one of the four sections so as to prevent the effective transfer of power from any one corner of the square to the corner diagonally opposite while still permitting 20 transfer of power from any corner to the adjacent corners.

A common characteristic of all known types of conjugate networks, whether of the preferred type just described or not, is that an impedance 30 simulating the impedance of the useful load must be connected to the conjugate network and when so connected receives as much power as is transmitted to the useful load. Accordingly, when the conjugate network of the preferred type or any 35 other type is employed for coupling to a common load the energy from a first signal source and from a second signal source the required balancing resistor or dump which must be connected to the conjugate network will receive as much energy 40 as the load thus requiring that the speech signal sources each generate twice the amount of power necessary for the load.

It is an object of the present invention to overcome the above disadvantage. It is a further 45 object of the present invention to provide a system which may radiate from a common antenna both speech signals and other signals with reasonable efficiency (i. e., without the dumping of large amounts of power) while at the same time 50 maintaining the essential characteristics of the signals free from the influence of any vacuum tubes, tuned circuits or other critical equipment used for supplying them.

More particularly, it is an object to provide 55 such a system wherein the phase and amplitude

of the beacon signals will be comparatively unaffected by the changing of tubes or retuning of the circuits used for speech radiation and wherein such effects as shall be produced shall not tend to alter the directional pattern of the beacon signals.

In brief, the present invention attains the above and other objects by applying the one set of signals and other signals to a common antenna or other load via a conjugate circuit having a dump resistor and by arranging that both the signals applied to a common load comprise substantial carrier components of roughly the same orders of magnitude and of accurately related phases, these phases being so regulated that the amount of power dissipated in the dump is small compared to the amount of power usefully radiated from the common antenna.

The exact nature of the invention may best be understood from the annexed sheet of drawings in which:

Fig. 1 is a schematic diagram of a system embodying my invention and adapted to radiate directive beacon signals and speech signals;

Fig. 2 is a similar diagram of another embodiment of my invention wherein the two signals radiated are both directive beacon signals;

Fig. 3 is a schematic diagram of a portion of a circuit which may be incorporated in the system of Fig. 2 in order to render the latter capable of simultaneously radiating two separate beacon signals and one speech signal; and

Fig. 4 illustrates two modulated sources connected to a common load by a circuit incorporating my invention.

Referring more specifically to Fig. 1, 1, 2 and 3 are three antenna elements horizontally disposed in a straight line with the outer elements 2 and 3 equally spaced from the center element 1. Preferably, each element is a loop of the type disclosed in Henney's "Radio Engineering Handbook" 1941, at page 601 and more fully described in my United States Patent No. 2,283,897, issued May 26, 1942, for "Antenna system," being thus adapted to radiate substantially pure horizontally polarized waves with substantially circular radiation patterns for each individual loop. In order to directionally radiate beacon signals modulated with 150 and 90 cycles, respectively, the circuit arrangement shown in the left hand portion of Fig. 1 is provided, this arrangement being essentially like that shown in my copending United States application, Serial No. 300,166, filed October 19, 1939, now Patent No. 2,307,184, issued January 5, 1943.

Briefly, this arrangement comprises the common source 4 whose output after passing the power amplifier 5 is applied to the lower corner of a bridge 6. This bridge 6 is of the type described in the above-mentioned United States patent, No. 2,147,809, the transposition 6a being arranged in the upper right hand arm thereof and a balancing dissipating impedance 7 substantially simulating the output impedance of the amplifier 5 being connected to the upper corner of the bridge so as to be essentially conjugate to the amplifier 5. A 2-wire transmission line 8 is connected to the right corner of bridge 6 and a similar line 9 is connected to the left hand corner thereof so that energy is delivered to each of these lines from the amplifier 5 although substantially no energy is delivered from this amplifier to the balancing impedance 7 because of the effect of the transposition 6a.

Loosely coupled to the transmission lines 8 and

9 are the short transmission line sections 8a and 9a whose effective electrical lengths are arranged to be varied cyclically at the rate of 90 cycles per second and 150 cycles per second, respectively, thus cyclically tuning these line sections to resonance at the frequency of source 4 and then detuning them again. As a result of such cyclical tuning and detuning of the coupled sections 8a and 9a the transmission of energy along the transmission lines 8 and 9 is cyclically varied so that the currents arriving in the upper portions of these lines 8 and 9 correspond to a carrier frequency equal to the frequency of source 4 modulated with 90 cycles tone and 150 cycles tone, respectively.

These tone modulated signals are then applied from lines 8 and 9 to the right and left corners of a combining bridge 10 whose lower corner is connected (through circuits more fully described hereafter) to the central antenna element 1 while the upper corner of this bridge 10 is connected to the outer antenna elements 2 and 3. As shown, the connection from the upper corner of bridge 10 to antenna element 3 includes the transposition 11 while the corresponding connection to antenna element 2 includes no such transposition thus insuring that the antenna elements 2 and 3 are excited in phase opposition to one another.

It should be noted that because of the transposition 10a of bridge 10 the energy delivered to the outer antennae 2 and 3 contains no unmodulated carrier component since this component is balanced out. Thus, the antenna 2, for example, contains only the side bands corresponding to the 90 and 150 cycle signals (e. g., $c+90$, $c-90$, $c+150$ and $c-150$ where c is the carrier frequency). The antenna 3 contains the same four components in opposite phase. The power delivered from the lower corner of bridge 10, on the other hand, contains a very strong component of carrier frequency c as well as of the four side bands above described.

Temporarily assuming that the lower corner of bridge 10 is directly connected to antenna 1 without any intervening bridge structure and assuming that the electrical length of the path from such lower corner of bridge 10 to antenna 1 is 90° longer than that of the path from the upper corner of bridge 10 to antenna 2, it will then be clear that the 90 cycle side band components radiated from antenna 1 will add to the radiation of the corresponding side bands from antennae 2 and 3 in that region to the north side of the course line WE while tending to oppose such radiation on the south side of such line. The reason for this is that the 90 cycle side bands must pass through one transposition in traveling from transmission line 8 to antenna 2 while encountering no transpositions but only a 90° greater length of line when traveling from transmission line 8 to antenna 1. Accordingly, the radiation of the 90 cycle side bands from antenna 2 will be 90° retarded with respect to the corresponding radiations from antenna 1. At the same time the corresponding radiations from antenna 3 will be 90° advanced compared to those from antenna 1 because of transposition 11. While the radiations from antennae 2 and 3 exactly cancel along the course line WE, the vectorial combination of the 90 cycle side bands from these antennae 2 and 3 will yield a resultant at any other given point in space by reason of the difference in path length from the two antennae to such given point. North of the course line WE, the radiations from

antenna 2 will arrive in a shorter time than those from antenna 3 thus effectively advancing the phase of the radiations from 2 and retarding the phase of those from 3 with respect to the phase of radiations from antenna 1. Therefore, the resulting radiation from antennae 2 and 3 combined will be in phase with the corresponding radiation from antenna 1 at any point north of the course line. Conversely, the 150 cycle radiation from the antenna 2 will be 90° advanced in phase with respect to the corresponding radiation from antenna 1. The resultant 150 cycle side band radiation from antennae 2 and 3 will tend to add to the corresponding radiation from antenna 1 in the region south of the course line WE while subtracting therefrom in the region north of this course line.

The apparatus so far described corresponds to that disclosed in detail in the above-identified application, Serial No. 300,166, a detailed understanding of the operation of such arrangement being desirable for full appreciation of the present invention.

The further apparatus 20—25 is associated with the apparatus already described for the purpose of applying speech signals to antenna 1 simultaneously with the beacon signals heretofore described. Such additional apparatus essentially comprises a speech source 20 (illustrated as a telephone transmitter but preferably comprising a microphone and suitable audio amplifier stages) connected to modulate an R-F amplifier 21 which is excited in parallel with the amplifier 5 from the carrier source 4. The speech modulated output of amplifier 21 which is preferably of the same order of magnitude as the output of amplifier 5 is transmitted through phase shifter 22 to the right-hand corner of conjugate bridge network 23, which is preferably of the type described in the above-mentioned United States Patent No. 2,147,809.

As shown in the drawings, the upper corner of the bridge 23 is connected to antenna 1 and the left hand corner thereof receives the proper beacon signals from the lower apex of combining bridge 10 earlier described. Thus, both the speech modulated signals from amplifier 21 and the combined carrier and four side bands of the beacon signals from combining bridge 10 are transmitted via bridge 23 to antenna 1. In order to insure conjugacy between the speech signals from amplifier 21 and the beacon signals from the lower corner of bridge 10, bridge 23 is balanced by means of transposition 23a and a balancing dissipating impedance 24 whose impedance as viewed from bridge 23 is equal to that of the antenna element 1 as viewed from this same bridge. A radio frequency voltmeter 25 is connected across the line between the lower corner of bridge 23 and the impedance 24 for a purpose hereafter to be described.

It should be noted that the signals from modulated amplifier 21 and the beacon signals from the lower corner of combining bridge 10 are not only of the same wavelength but both contain a substantial component of carrier frequency derived from the common source 4. In the case of the beacon signals this carrier frequency component has a phase dependent upon the characteristics of power amplifier 5 and this phase may vary due to adjusting of the tuned circuits of this amplifier or even, to some extent, due to the two variations in the tube characteristics thereof. In the case of speech signals from amplifier 21 also the phase of the carrier accom-

panying these speech signals is dependent upon the characteristics of amplifier 21 and thus can be varied due to adjusting the tuned circuits of this amplifier or even by virtue of changes in the tube characteristics thereof. The phase shifter 22 is provided to take care of these variations in phase and is intended to be set so that the phases of the carrier components in the speech signals and in the beacon signals are alike at the points 5 where these signals are applied to the right and 10 left corners of bridge 23, respectively. If this 15 phase relationship is attained and if the magnitudes of the carrier components of the two signals are alike, it will then follow that no carrier 20 frequency energy will be dissipated in impedance 24 because of the effect of transposition 23a. Even if the carrier power from speech amplifier 21 be assumed to be only half as great in amplitude as the carrier power from the bottom of 25 bridge 10 (so that the corresponding voltages are in the ratio of .707 to 1) it can readily be seen that the voltage at the upper corner of bridge 23 will correspond to 1+.707 (i. e., to 1.707) while at the lower corner it will correspond to 1-.707 (i. e., to .293). The corresponding powers will 30 be proportional to $(1.707)^2$ and $(.293)^2$ respectively, being thus in the ratio of 2.9 to .086, i. e., about 34 to 1. Thus, when the carrier component from amplifier 21 is only half as great as 35 the corresponding power from bridge 10 it still appears that the power dissipated in dump 24 is less than 3% of the carrier power usefully radiated from antenna 1.

With respect to the side bands of the speech 35 signals and the beacon signals it is true that substantially 50% dissipation occurs in impedance 24 but in most cases the average side band power is considerably smaller than the average carrier power and therefore the total amount of wastage 40 is a comparatively small percentage of the total energy usefully radiated from antenna 1.

One great advantage of the arrangement in Fig. 1 is that phase variations introduced in the amplifiers 5 and 21 (by virtue of the adjusting 45 of the associated tuned circuits or variations in the tube characteristics thereof) do not alter either the position of the course line defined by the beacon signal or the shape of the radiation pattern in respect to relative strengths of the 50 150 and 90 cycle signals at any points in space. It is also true that if the phases of the carrier components delivered by the amplifiers 5 and 21 vary in opposite sense by a considerable number of degrees a substantial dissipation of power in 55 impedance 24 will result since the carrier components arriving at the right and left corners of bridge 23 will no longer be in phase. Such a result, however, is by no means as serious as a distortion of a beacon radiation pattern. Furthermore, the dissipation of energy in the dump 60 24 is constantly indicated by the meter 25 and therefore any person adjusting the tuned circuits associated with either amplifier 5 or 21 will be immediately apprised of any incorrect phase 65 relationship.

It should be observed that even if a very large 70 difference in phase exists between the carrier components from amplifiers 21 and 5 the side band components of the beacon signal radiated from antenna 1 will still be properly phased with respect to the corresponding side band components of the beacon signal radiated from antennae 2 and 3. Also, these side band components will be properly phased with respect to the portion 75 of the carrier component which is derived

from amplifier 5. If, therefore, the two carrier components supplied by amplifiers 5 and 21 are of equal magnitude, then a phase shift as much as 60° between the phases of the carrier components supplied from the two amplifiers will result in a phase shift of only 30° between the resulting combined carrier radiated from antenna 1 and the beacon side bands. Such a phase shift will not alter the beacon pattern at all (in view of the fact that the side band components in the several antennae are properly phased) but instead will only decrease the efficiency of demodulation at the receiver by decreasing the amount of useful carrier component available for demodulating the signals. This effect is not at all serious unless the phase relationship between the carriers becomes as great as 180° , in which case the resultant carrier being 90° to the side bands would not be useful for producing demodulation in the receivers. It is clear, however, that the phase shifts of the amplifiers are not likely to equal 180° especially with the constant check provided by meter 25.

With respect to the speech frequencies the shifting of the carrier with reference to the side bands is also somewhat undesirable since it tends to produce harmonic distortion. Such distortion is unimportant if the percentage modulation is small. In the system shown, moreover, half the carrier component is derived from amplifier 21 and therefore does not shift.

Thus a phase shift of 60° between the two carrier components would only shift the combined carrier by 30° with respect to the speech side bands. These two factors (i. e., the effect of low modulation percentages in preventing distortion and the fact that only half the phase shift between carriers appears as a phase shift between the combined carrier and the side bands) both tend to reduce the amount of distortion encountered in practice. Thus, as a practical matter, under ordinary conditions with a modulation percentage around 80% a phase shift as large as 50° between the two carriers will not produce an intolerable percentage of harmonic distortion in the speech signal.

Although the invention has so far been described as used for radiating speech signals and beacon signals from one common antenna element (e. g., antenna element 1 of the array 1, 2, 3), the invention is also capable of other uses. Thus, for example, it may be used for radiating two separate beacon signals from a common antenna, such an arrangement being illustrated in Fig. 2.

Referring more particularly to Fig. 2 the components 1', 2', 3', 4', 5', 6', 6a', 7', 8', 8a', 9', 9a', 10', 10a' and 11' correspond exactly to the elements of Fig. 1 having corresponding unprimed designations. These elements together constitute a beacon defining a west-east course line exactly as described in connection with Fig. 1.

The bridge 23' with its transposition 23a and its dump 24' and its meter 25' serve, as in the case of Fig. 1, to transmit to the central antenna 1' not only the appropriate beacon signals (consisting of a carrier component and four side band components having the frequencies $c+150$, $c-150$, $c+90$ and $c-90$, respectively), but also an additional independent set of signals based upon the same carrier frequency. In the case of Fig. 2 such additional independent set of signals is assumed to be another set of beacon signals rather than a speech channel as in Fig. 1.

The equipment for providing the additional

beacon signals comprises the power amplifier 105; the two transmission lines 108 and 109 with their modulating equipments 108a and 109a; the bridge 106 for transmitting the power to these lines 108, 109 from the amplifier 105; such bridge being provided with a transposition 106a and a balancing impedance 107 in order to prevent the modulator of 109a of channel 109 from reacting on the channel 108 or vice versa; the combining bridge 110 with its transposition 110a and the antennae 102 and 103. All of this equipment operates essentially like the correspondingly numbered equipment in Fig. 1 (the number 108 being considered as corresponding to the number 8, etc.). The side antennae 102 and 103 are fed anti-phasally with the four side bands corresponding to a 1020-cycle modulation and a 1300-cycle modulation, these side bands having the frequencies $c+1020$, $c-1020$, $c+1300$, and $c-1300$. The central antenna 1' is fed from the lower corner of bridge 110a with appropriate signals having a strong carrier component and also including the same four side bands which are radiated from antennae 102 and 103. The bridge 23' combines the signals from the lower corner of bridge 110 with those from the lower corner of bridge 10'. Each of these signals to be combined contains a substantial carrier component and these components are of the same order of magnitude (i. e. the ratio of the powers is less than 10:1). The phases of the carrier components arriving at the left hand and right hand corners of bridge 23' should be alike and this condition may be attained by adjusting the tuned output circuits of amplifiers 5' and 105 to produce the desired phase relation. In case a more convenient adjustment is desired, a phase shifter may be provided just ahead of amplifier 5' or 105 or immediately following either or both of these amplifiers. The meter 25' will serve to show when the desired phase condition is reached, since this meter will read zero or a minimum when the carrier components arriving at the left and right corners of bridge 23' are in phase. In the system of Fig. 2, an east-west course line is defined by the equality of the 150 cycle modulated signals and the 90 cycle modulated signals, while a north-south course line is defined by the equality of the 1020 cycle modulated signals and the 1300 cycle modulated signals. For properly generating the beacon patterns to define these course lines, antennae 2' and 3' and 102 and 103 should be fed in phase quadrature with respect to the central antenna 1'. Accordingly, the electrical length of the path from the upper corner of bridge 10' to antenna 2' may be 90° shorter than the length of the path from the lower corner of bridge 10' to antenna 1'. Similarly, the length of the electrical path from the upper corner of bridge 110 to antenna 103 may be 90° shorter than the length of the path from the lower corner of bridge 110 to antenna 1'. These relationships may be satisfied by suitably choosing the lengths of the transmission lines. If desired, however, phase-shifter equipment can be inserted between the upper corner of bridge 10' and the antenna array and other phase-shifting equipment may be inserted between the upper corner of bridge 110 and the antenna array. Such phasing equipment, if provided, would be adjusted for initially aligning up the courses and would thereafter not be disturbed.

If it is desired to combine more than two signals upon a common antenna, this may be done by extending the principle of the present invention. Fig. 3 illustrates how Fig. 2 could be modified to

embody such a system, the circuit of Fig. 3 being intended to be substituted for the rectangle 50 in Fig. 2. As will be shown by comparing Fig. 3 with the right hand portion of Fig. 1, the amplifier 221 which is modulated by speech source 220 feeds its speech modulated output to bridge 223 in essentially the same way that amplifier 21 fed its output to bridge 23 in Fig. 1. In the system of Fig. 2 as modified by Fig. 3, the additional input which is combined with the speech signals in bridge 223, arrives from the lower corner of bridge 110 and in order to minimize losses in the dump 224, the phases of the arriving carrier components may be adjusted by adjusting the tuned output tank of amplifier 105 of modulated amplifier 221, or both. If desired, however, a phase shifter may be included before or after either or both of these amplifiers. The output from bridge 223 is applied to the right hand corner of bridge 23' where it is combined with output from the lower corner of bridge 10'. Preferably, the amplitudes of the carrier components arriving at the upper and lower corners of bridge 223 (from amplifier 221 and the lower corner of bridge 110) should be approximately equal in magnitude and should each be approximately half the amplitude of the carrier components delivered from the lower corner of bridge 10'. Thus, the combined carrier delivered from the left corner of bridge 223 will be of substantially the same amplitude as the carrier delivered from the lower corner of bridge 10' and therefore substantially no dissipation of carrier energy will occur in the dump 24'.

In the circuits of Figs. 1, 2 and 3 a circuit according to my invention has been shown for combining beacon signals and speech signals. The circuit is useful, however, for combining modulated radio frequency energy from any two sources.

In Fig. 4 is shown a first source of carrier modulated signal 401 and a second source of modulated signal 402. These sources are of the same radio frequency but carry thereon different signal energies. The modulations may be of any desired type, for example, they may be intermediate carriers modulated with signals to be applied to a multiplex line 403. Sources 401, 402 are applied to the opposed diagonals of bridge 404, having a transposition 405. A balancing dissipating network 406 is coupled to the bridge terminal opposed to load line 403 and is proportioned to match the impedance of the load. Thus, two sources are interconnected so as to have no reaction one on the other, and yet relatively wide variations in amplitude and phasing of the signals may be permitted without destroying the substantial advantages of the system.

If desired, 401, 402 or both, may include amplitude and phase adjusting means so that adjustment may be made until minimum current is applied to dissipating network 406 as indicated in meter 407.

Although it is preferred that the two carrier components to be combined in any one of the bridges (e. g. 23, 23', 223 or 404) are preferably cophasial and of equal magnitudes, very wide departures from this condition may be tolerated while still giving surprisingly small losses in the dump balancing resistor. Thus, for example, a 4:1 power ratio will result in a dissipation of only 10% of the total power; 90% of this power being transmitted to the useful load. Even a 10:1 power ratio results in wasting only about 21% of the total power (which is a very substantial improvement over the 50% power wast-

age incurred with the ordinary conjugate circuit arrangements, without controlling the phases of the carriers). In respect to phasing, also a considerable latitude is permissible. Thus if the two carrier components to be combined are equal in power, a phase divergence of as much as 30% causes the dissipation of only about 6½% of the total power while even a phase divergence as large as 60° causes the dissipation of only about 25% of the total power.

Although the invention has been particularly described for combining two signals one of which is a beacon signal, it can also be used for combining two signals of any type, for example, phase and amplitude modulated signals employing the same carrier or telegraph and telephone signals based on the same carrier.

For convenience, the illustrated embodiments of the invention show the modulation as effected at audio-frequencies (i. e. by audible frequency tone modulators producing power tones of 90 cycles, 150 cycles, 1020 cycles or 1300 cycles, or by speech frequency modulating equipment. It should be understood, however, that the modulation may be performed at super-audible or sub-audible frequencies and may consist of or include the process of keying in A-N rhythm or other rhythm. Thus, the expression "modulation" as used in the appended claims should be interpreted in its broader sense to include all modifications of the amplitude, phase, or frequency of the carrier by any of the commonly used processes ordinarily referred to as modulation or keying.

Although certain embodiments of the invention have been shown and described for purposes of illustration, it will be understood that variations, adaptations and modifications thereof occurring to one skilled in the art may be made without departing from the scope of the invention as defined by the appended claims.

What is claimed is:

1. A system for simultaneously applying two signals on the same carrier frequency wavelength to a common useful load which comprises a first signaling means for producing a first side band component and a first carrier component, second signaling means for producing a second side band component and a second carrier component, common load means, a balancing dissipating element simulating the impedance of said common load means, a balanced network connected to transfer energy from said first and second signaling means to said common load means and with a relative phase reversal to said balancing element while maintaining substantial conjugacy between said first and second signaling means, and carrier synchronizing means for maintaining said first and second carrier components at the same frequency and in a predetermined phase relation such as to minimize the absorption of carrier energy in said balancing element.

2. A system for simultaneously applying two signals on the same given carrier frequency wavelength to a common useful load which comprises a first signaling means for producing a first side band component and a first carrier component of said given wavelength, second signaling means for producing a second side band component and a second carrier component of said given wavelength, common useful load means, a balancing element simulating the impedance of said load means, a balanced network connected to transfer energy from said first and second signaling means to said common useful

load and with a relative phase reversal to said balancing element while maintaining substantial conjugacy between said first and second signaling means, and means for adjusting the phases of said first and second carrier components thereof as measured at the input to said balancing element substantially into opposition.

3. A system for simultaneously applying to a common useful load two signals on the same carrier frequency wavelength which comprises first signaling means for producing a first side band component and a first carrier component, a second signaling means for producing a second side band component and a second carrier component, said carrier components being of the same radio frequency, a dissipating balancing element simulating the impedance of said common load, a balanced network connected to transfer energy from said first and second signaling means to said common load and with a relative phase reversal to said balancing element while maintaining substantial conjugacy between said first and second signaling means, carrier synchronizing means controlling said first and further signaling means to maintain the phases of said carrier components substantially opposite as measured at the terminals of said balancing element.

4. A system according to claim 3 wherein said first and second signaling means are adjusted to transmit to said balanced network carrier components of substantially the same order of power.

5. A system according to claim 3 wherein said first and second signaling means are adjusted to transmit to said balanced network carrier components, the ratio of whose powers is less than 3 to 1.

6. A system for simultaneously applying to a common load two signals on the same carrier frequency wavelength which comprises first signaling means for producing a first side band component and a first carrier component, second signaling means for producing a second side band component and a second carrier component, a dissipating balancing element simulating the impedance of said common load, a balanced network connected to transfer energy from said first and second signaling means to said common load and with a relative phase reversal to said balancing element while maintaining substantial conjugacy between said first and second signaling means, carrier synchronizing means controlling said first and second signaling means to maintain the frequency of the carrier components identical and the phases of said carrier components within 60° of being opposite.

7. A system for simultaneously applying two signals on the same common carrier frequency to a common load comprising a first source of modulated energy having a carrier component of said common frequency and side band components, a second source of modulated energy having a second carrier component of said common frequency and other side band energy, a dissipating element simulating the impedance of said common load, a balanced bridge having four diagonally arranged points, means for applying energy from said first modulated energy source and said second modulated energy source to opposite diagonal points of said bridge, means for coupling said load to another of said diagonal points to receive carrier frequency energy and side band frequency energy from both said sources, means for coupling said dissipating network to the other said point on said bridge diagonally opposite to said

load connection, means in said bridge for producing a phase reversal of energy from one of said sources intermediate the connection points of said source and said dissipating network to the said bridge and means for maintaining energy supplied from said sources to said bridge substantially in phase coincidence whereby carrier frequency energy is substantially balanced out at the input of said dissipating network and substantially only side band energy is dissipated in said network.

8. A system in accordance with claim 7 wherein each of said sources comprise independent amplifier arrangements and said means for maintaining energy applied from said sources to said bridge substantially in the same phase comprising a phase shifting network for adjusting in phase energy from one of said modulated sources with respect to energy from the other of said sources.

9. A system for simultaneously applying carrier energy of the same frequency but modulated with different characteristic signals to a common radiating means, said signals each comprising a carrier frequency component and respective side band components comprising a balanced four arm bridge circuit, means for coupling said radiating means to a first point on said bridge, a dissipating network means for coupling said dissipating network to a second point diagonally opposite said first point, means for applying carrier and said band components from each of said sources to respectively opposite terminal points of said bridge to supply carrier frequency energy and side band frequency energy from both sources to said common radiating means, and means for maintaining energy from both said sources over said network to said dissipating network in such phase relationship that said carrier components from the respective sources are substantially in phase opposition whereby substantially no carrier frequency energy is dissipated in said network, said side band components both being applied to said network for dissipation.

10. The method for simultaneously applying two signals on the same wavelength to a common useful load over a balancing network designed to maintain conjugate relation between said signals which comprises producing a first carrier component at said wavelength and an associated first side band component, producing a second carrier component at said wavelength and a second associated carrier component, applying said first carrier component, said first side band component, said second carrier component and said second carrier side band component to said load over said network in such phase relation that said carriers are substantially in phase coincidence in said load and applying said components over said network to said dissipating network in such phase relation that the first and second carrier components are substantially in phase opposition at the input in said dissipating network whereby substantially only side band energy is dissipated in said dissipating network.

11. The method in accordance with claim 10 the further step comprising adjusting the relative phase in said first and second carrier components to maintain the desired phase relationship therebetween at said load and said balancing network.

12. A system for simultaneously radiating course indicating signals and voice signals simultaneously from the same antenna system on the same carrier frequency comprising a first carrier frequency source, means for modulating en-

13

ergy from said carrier frequency source with beacon signals, means for applying said signal modulated energy only to certain of said antenna units, a second carrier frequency source, means for voice modulating said second carrier frequency, a balancing network, a common antenna unit cooperatively arranged with respect to said certain antenna units, means for applying modulated energy from said course indicating source and from said voice modulated source over said balancing network to said common antenna and for supplying energy from said sources over said balancing network to said dissipating network

14

and means in said balancing networks for maintaining carrier frequency energy from both of said sources substantially in phase coincidence at said common antenna and substantially in phase opposition at said dissipating network.

5 13. An arrangement in accordance with claim 12 further comprising means for shifting the phase of said voice modulated carrier energy before application to said balancing network to assure proper phase relation of said carrier energy at said antenna and at said dissipating network.

ANDREW ALFORD.
